UNITED STATES PATENT OFFICE.

JOHN R. JEWETT, JR., OF WOOD RIVER, NEBRASKA.

RURAL MAIL BOX.

Application filed June 13, 1921. Serial No. 476,971.

To all whom it may concern:

Be it known that I, JOHN R. JEWETT, Jr., a citizen of the United States, residing at Wood River, in the county of Hall and State 5 of Nebraska, have invented certain new and useful Improvements in Rural Mail Boxes, of which the following is a specification.

My invention relates to mail boxes and is particularly designed for filling the practical 10 needs of boxes used in rural mail delivery.

The principal object of my invention is the provision of a rural mail box constructed and equipped to receive letters and parcels of 15 all sizes from both the postman and sender with manually-operated indication to impart any desired information about such mail to the collector thereof.

A further object is the connection of the 20 usual elevated flag indicating the deposit of mail in the box with the door in such manner as to insure the lowering of the flag when the deposited mail is removed, thereby preventing the annoyance of false indication 25 with its attendant unnecessary visits to the box.

A further object is the arrangement on 30 the inside of the door of the box of semi-automatic indicating means for informing the collector of mail of the desires of the sender concerning the method of delivery in conjunction with fastening means for retaining money intended for payment of postage or purchase of additional stamps.

Other objects and advantages will be apparent from the following description, wherein reference is had to the accompanying drawings illustrating a preferred embodiment of the invention, and in which 35 similar reference numerals designate similar parts throughout the several views.

In the drawings:

Fig. 1 is a perspective view of my improved mail box in position for use; Fig. 2 40 is a vertical central section therethrough; Fig. 3, 4 and 5 are detailed sectional views taken substantially on the lines 3—3, 4—4 and 5—5 of Fig. 2; Fig. 6 is a plan view of the door of the box when in opened position, and Figs. 7 and 8 are detailed sectional views taken respectively on the lines 7—7 45 and 8—8 of Fig. 6.

Referring to the drawings, the numeral 5 designates a box casing preferably formed 50 of sheet metal galvanized or painted for protection against the weather, and formed with

its sides, floor, roof and one end wall firmly fastened together with watertight joints, as by riveting or soldering. The other end wall is formed with an upper portion 6 secured to 60 the roof of the casing and a lower portion pivoted adjacent its bottom to form a door 7 for the introduction of parcels and the removal of any mail placed into the box. Letters may be inserted into the box through 65 a slot 8 in the portion 6 without opening the door, this slot being normally covered by a hinged flap 9 for protection against the elements. A handle 10 is provided for ease in 70 opening the door 7 and connection is made from the door to the flag signaling device 11 to insure lowering of the flag whenever the door is opened. This connection comprises the rod 12 pivoted at one end to the inside 75 of the door and at the other end to the slide 13 mounted for longitudinal movement in brackets 14 secured to the side wall of the casing 5. A slot formed in the side wall limits the travel of the slide and rod. An outwardly-extending lug 15 on the slide 13 is arranged to contact the staff of the flag 80 11 which is pivoted, as at 16, adjacent the lower edge of the side wall. A spring clip 17 fixed on the side wall adjacent its upper edge is designed to hold the flag in elevated 85 position to signal that mail has been deposited in the box. When in such elevated position (see Fig. 1) the lug 15 contacts the flag staff. When the door 7 is opened to remove such mail the slide 13 is moved forwardly by the rod 12 and the lug 15 thereon 90 swings the flag downwardly during the travel of the slide. A suitable stop, as 18, supports the flag in its lowered position. As 95 herein shown, the stop 18 is bent outwardly and then upwardly to provide a hanger for parcels while a similar hook 19 is provided adjacent the lower edge of the casing 5 to receive parcels too bulky to be placed inside 100 the box.

To impart to the postman all information relative to the method of delivery desired for the mail left in the box for collection, as whether a letter is to be registered or provided with a special delivery stamp, I provide a convenient semi-automatic indicator on the inner face of the door 7. As herein shown, this comprises a pivoted hand 20 (see Fig. 6) adapted to register with a dial 21 having graduations marked with the various styles of delivery for letters or parcels, as Special Delivery, C. O. D., Insured, etc., 110

and also with graduations marked to designate the number and denominations of stamps desired to be purchased. When the sender places a letter or parcel in the box 5 he turns the hand 20 to register with the desired graduation on the dial 21, the hand being held by friction wherever set. To firmly secure the money simultaneously placed for payment of postage I provide a 10 spring clip 22 to receive paper money, clasping it between the face of the door and the clip, and for the retention of metal coins a pair of spring clips 23 with their free ends upturned and engaging each other 15 (as shown in Fig. 7). The upper edges of the clips 23 flare outwardly and a coin inserted between the edges will be clasped between the upturned end portions.

From the foregoing description it will be 20 apparent that I have provided a mail box well adapted to satisfy the needs of rural delivery and collection boxes. The postman may readily insert letters through the slot 8 or parcels by opening the door 7, or if 25 the parcels are too large for the interior of the box they may be hung upon the hooks 18 or 19 upon the side of the box. He then swings the flag 11 upright to signal the deposit of mail. When the owner visits the 30 box in response to the signal the act of opening the door 7 automatically lowers the flag, thereby obviating any forgetting to lower the flag with a consequent useless trip to the box later. When a letter or parcel 35 is placed in the box for collection by the postman, he may indicate on the dial 22 exactly how he desires such mail forwarded and may safely leave coins or bills to pay for the postage, or additional stamps may 40 be purchased with assurance that the postman will understand his wants.

While it will be apparent that the illustrated embodiment of my invention herein disclosed is well calculated to adequately 45 fulfill the objects primarily stated, it is to be understood that the invention is susceptible to variation, modification and change within the spirit and scope of the subjoined claims.

50 Having described my invention, I claim:

1. A rural mail box comprising a casing, a door hinged thereto, a flag to signal deposits of mail in the box pivoted to the casing, a connection between the door and flag 55 to lower the flag when the door is opened, including a rod pivoted to the door, and a slide connected with the rod and adapted to engage the flag.

2. A rural mail box comprising a casing, 60 a door hinged thereto, a flag to signal de-

posits of mail in the box pivoted to the casing, a connection between the door and flag to lower the flag when the door is opened, including a rod pivoted at one end to the door, a slide mounted on the casing and pivotally connected to the other end of the rod, and a lug on the slide arranged to contact the flag when in elevated position. 65

3. A rural mail box comprising a casing, a door hinged thereto, a flag to signal deposits of mail in the box pivoted to the casing, a connection between the door and flag to lower the flag when the door is opened, including a rod pivoted at one end to the door, a slide mounted on the casing and pivotally connected to the other end of the rod, the casing having a slot in which the rod travels and a lug on the slide arranged to contact the flag when in elevated position. 70

4. A rural mail box comprising a casing, a door hinged thereto, a flag to signal deposits of mail in the box pivoted to the casing, a spring clip fixed on the casing to releasably hold the flag in elevated position, 75 a connection between the door and flag to lower the flag when the door is opened, including a rod pivoted at one end to the door, a slide mounted on the casing and pivotally connected to the other end of the rod, and a lug on the slide arranged to contact the flag when in elevated position. 80

5. A rural mail box comprising a casing, a door hinged thereto for deposit and removal of mail, and means on said door for indicating to the postman the desired form of delivery of deposited mail, including a dial on the door having graduations bearing indicia for the various forms of delivery, and quantity and denominations of stamps to be purchased an index hand pivoted on 85 said door and turnable to any of such graduations, and clips fixed on the door to hold money for payment of postage. 90

6. A rural mail box comprising a casing, a door hinged thereto for deposit and removal of mail, and means on said door for indicating to the postman the desired number and denomination of stamps to be purchased, including a dial on the door having 95 graduations for various numbers and denominations of stamps, an index hand movably mounted on said door to register with any of such graduations, and clips on said door to hold money for purchase of stamps. 100
